UNITED STATES PATENT OFFICE.

JUDSON A. BALDWIN, OF SHELBURNE, VERMONT.

REFRIGERATOR.

SPECIFICATION forming part of Letters Patent No. 276,752, dated May 1, 1883.

Application filed January 15, 1883. (Model.)

To all whom it may concern:
Be it known that I, JUDSON A. BALDWIN, a citizen of the United States, residing at Shelburne, in the county of Chittenden and State 5 of Vermont, have invented certain new and useful Improvements in Refrigerators; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

My invention relates to an improvement in 15 refrigerators; and it consists in the combination of a pivoted cut-off, which is located in the opening made in the top of one side of the ice-box, with a connecting-rod which is attached thereto, and which is provided with one or 20 more projections, suitable springs for pressing downward upon the operating-levers, and suitable crank-levers which are operated at their lower ends by the doors of the provision-room, and which catch at their upper ends over the 25 operating-rod for the purpose of raising the rod and opening the cut-off, as will be more fully described hereinafter.

The object of my invention is to automatically open and close the cut-off that is placed 30 between the ice-chamber and the provision-room, so that when the door of the provision-room is opened a spring-actuated lever will instantly cause the cut-off to close, so as to prevent warm air from entering the ice-chamber, 35 and to open the cut-off as soon as the door is closed, so as to restore the circulation of air.

In the accompanying drawings, in which similar letters of reference indicate like parts, Figure 1 is a perspective of a refrigerator embodying my invention. Fig. 2 is a vertical cross-section of the same.

A represents a refrigerator provided with the ice-chamber B in one corner. Through the upper inner side of this ice-chamber is made a 45 suitable opening, C, through which the warm air which has risen to the top of the provision-chamber passes into the ice-chamber. This chamber has an inclined bottom, as shown by dotted lines in Fig. 1, so as to carry off the water from the melting ice, and leading from this bottom, at one side, is a suitable air flue or passage, through which the cold air from the ice-

chamber passes down into the provision-chamber in the usual manner. In the upper opening, C, is placed the pivoted cut-off D, which is so hung that it effectually closes the opening, except when it is forced open by means of the action of the rod E, when the door of the provision-chamber is closed. The upper end of this rod is fastened to a short connecting rod or link, which is hooked into an eye in the lower edge of the cut-off D, and the lower end of the rod passes through the upper end of all of the crank-levers F, which are pivoted inside of the provision-chamber. If there is only one 65 door, this rod will pass through only a single crank-lever; but if there are two or more doors the rod will pass through two or more crank-levers, as is here shown. Opposite each door or pair of doors the crank-lever F will be pivoted in such a position that when the door is closed it will strike against the lower end of the lever and tilt its upper end upward. Where there are two or more doors, placed one above the other, the operating-rod will have a suitable projection secured rigidly to it opposite the upper lever, so that when this crank-lever is left free to move its upper end will strike upon the top of the projection, so as to force the operating-rod downward and through the rod 80 to close the cut-off. The lower end of the operating-rod is bent or turned after it passes through the lower one of the crank-levers, so that when the upper end of this crank-lever is forced downward by its spring it will carry the 85 operating-rod with it. Secured to this operating-rod opposite the upper one of the crank-levers is a suitable projection, upon the top of which the upper end of the top crank-lever will be made to catch. Secured inside of the 90 provision-chamber at any suitable point is a suitable spring, G, for each operating-lever, and which is made to catch in or against the levers which operate the rod. The free ends of these springs are made to operate the crank-levers, so as to exert a constant downward pressure upon them and keep the levers pressed downward when they are left free to move. Whenever one of the doors of the provision-chamber is opened the spring instantly forces 95 the crank-lever downward, and when the door is closed it strikes against the lower end of the crank-lever and forces its upper end upward for the purpose of moving the operating-rod up- 100

ward at the same time, and thus operate the cut-off. These projections are fastened to the operating-rod below each crank-lever, except the bottom one, where the end of the rod is bent.

5 All of the crank-levers elevate the rod E by frictional contact, so that when any one of the levers is moved the rod will be made to elevate the cut-off D. When all of the doors are closed the pressure of the springs is received upon 10 the crank-levers alone, and the operating-rod will be held in a raised position by the frictional contact of one or more of them against it. As soon, however, as one of the doors is opened the pressure of the spring-actuated lever is at once brought to bear upon the projections on the rod opposite the door, so as to force it downward, when the rod will move through the other operating-levers, and thus 15 operate the cut-off.

20 Instead of the springs here shown, weights may be used for the same purpose. Each weight will then have a hole made through it and be passed over the rod E, and the ends

of the crank-levers F will then be made to catch under the weights and raise them up- 25 ward.

What I claim, and desire to secure by Letters Patent, is—

In a refrigerator, the combination of the doors of the provision-chamber, the ice-chamber B, a cut-off, D, a connecting-rod, E, attached thereto, and which passes down through the upper end of each of the crank-levers F, a projection on the rod below the upper end of each lever, and springs G, which have their 30 free ends attached directly to the crank-levers F, so as to keep their upper ends forced constantly downward when they are left free to move, substantially as shown and described.

In testimony whereof I do affix my signature 40 in presence of two witnesses.

JUDSON A. BALDWIN.
